R. P. PERRY,
RETAINER MEMBER FOR ROOFING FABRIC ROLLS,
APPLICATION FILED MAR. 12, 1918.

1,312,202.

Patented Aug. 5, 1919.

UNITED STATES PATENT OFFICE.

RAY P. PERRY, OF UPPER MONTCLAIR, NEW JERSEY, ASSIGNOR TO THE BARRETT COMPANY, A CORPORATION OF NEW JERSEY.

RETAINER MEMBER FOR ROOFING-FABRIC ROLLS.

1,312,202.

Specification of Letters Patent. Patented Aug. 5, 1919.

Application filed March 12, 1918 Serial No. 221,935.

To all whom it may concern:

Be it known that I, RAY P. PERRY, a citizen of the United States, residing at Upper Montclair, in the county of Essex and State of New Jersey, have invented certain new and useful Improvements in Retainer Members for Roofing-Fabric Rolls, of which the following is a specification.

In the application of Curtis J. Rothermel 10 co-pending herewith, filed May 19, 1917, and bearing Serial No. 169,788, there is described a retainer means for positioning and retaining within the hollow portion of a roll of construction or roofing material the packages of cement, nails, etc., commonly called 15 "trimmings" which are used in applying the material to the roof, wall or other portion of the structure on which the same is to be used. As disclosed in this application, retainer means are employed consisting of a 20 plurality of end members associated with lateral spring or tension means whose transverse dimension is larger than the interior diameter of the cavity of the roll of construction material. The end members are 25 smaller, however, than such interior diameter so that when the retainer member is introduced into the cavity of the roll the lateral tension means will exert pressure on 30 the inner wall of such cavity and will accordingly serve to locate or position such retainer member. Upon inserting such retainer member into the cavity of the roll the packages of cement, nails, etc., are introduced 35 therewith, being inserted between the end members, and are thereby retained and positioned within the roll.

The object of my present invention is to 40 provide simplified and improved means of the general character described in the application above referred to. Instead of using two end members connected or associated with lateral tension means, the whole being inserted into the cavity in the roll of construction or roofing material in which the 45 retaining means are to be positioned to hold in place the packages of cement, nails, etc., I may use and arrange either one or both end members as receptacles in which to place 50 the cement, nails, etc., to be used in applying the construction material. By thus making one or both end members in the form of receptacles or containers, I effect a considerable economy of material and bring 55 about increased ease of manufacture, thereby

providing a simple and effective device for my purpose.

Referring to the drawing wherein I have illustrated several species of my invention:

Figure 1 shows in side elevation one 60 species of my invention;

Figs. 2, 3, 4 and 5 show in side elevation other species of my invention;

Fig. 6 shows a plan view of the disk shown in Fig. 5;

Fig. 7 shows the retainer means illustrated in Fig. 1 in position within the roll of roofing material, the roll being shown in section and the retainer means in side elevation; and

Fig. 8 shows in side elevation another species.

Referring now to the species shown in Fig. 1, *a* indicates a plurality of lateral tension members in the form of bowed springs having the bent ends *e*, *e*. At one end the lateral tension means or members *a* fit, by means of the bent ends *e*, *e*, into openings *o* in ears or extensions *E* forming a part of or attached to the end member *b* which is constructed in the form of a container or receptacle to hold cement, for example. The other end member *d*, which may be a disk-shaped piece of wood or other suitable material, positions the other extremities *e'*, *e'* 85 of the lateral tension members *a*, *a*. Between the members *b* and *d* is located the package *c* containing the rest of the "trimmings". Or, if desired, it is obvious that a plurality of such packages *c* may be located 90 between the members *b* and *d*.

In Fig. 7 I have shown the retainer member just described in position within the roll *R* of roofing or construction material. The member is held in position by the lateral 95 pressure exerted by the lateral tension members *a*, *a* against the walls of the substantially cylindrical cavity *S* within the roll. While the diameter of the parts *b*, *c*, *d* is less than that of the cavity *S*, the maximum 100 transverse dimension between the members *a*, *a*, is substantially greater than the diameter of the cavity so that the members *a*, *a* are put under compression when the retainer means is inserted into the cavity, 105 whereby the said means are positioned within the roll.

In Fig. 2 the lateral tension members *a*, *a*, are connected to two end members *b*, and *c*, each of which is in the form of a re- 110

ceptacle. In this arrangement the ends e_1 , of the members a_1 , adjacent the outer surface of the container b_1 , are bent over such surface so as to press against and position 5 the same. The other ends e_2 of the members a_1 pass through apertures o_1 in the ears or lugs E_1 forming parts or extensions of the container e_1 .

As shown in Fig. 3, illustrating another 10 modification of my invention, the lateral tension members consist of a single integral substantially U-shaped member a_2 having bent portions or ends e_3 fitting into apertures o_2 in the ears E_2 forming a part of or 15 connected to the end member b_2 which serves also as a receptacle. e_2 is also an end member serving, at the same time, as a receptacle or container for part of the "trimmings", 20 said receptacle e_2 being positioned with respect to the tension member a_2 by the transverse or end section a_1 of the tension member a_2 .

In Fig. 4 there is shown another modification of my invention. In this case the 25 tension means a_3 , a_3 consists of a substantially continuous elongated tension member having the connecting portions a_4 , a_4 which serve as ends or stops against which rest the containers or receptacles b_3 and c_3 30 for the cement, nails, etc., constituting the "trimmings" for the roll of roofing or construction material. The free ends 1, 2 of the lateral tension means a_3 are connected together in any suitable manner, as by 35 "hooking" said ends together, in the manner illustrated in the drawing.

In Fig. 5 is illustrated another modification of my invention in which the lateral tension members consist of a single U-shaped 40 member a_5 , connected by an end piece d_1 , similar to d , Fig. 1, thus retaining the receptacles b_4 and c_4 . In this view is shown a disk k of metal interposed between the receptacles b_4 and c_4 . The disk k has radial 45 slots s extending from its circumference as shown in Fig. 6 in order to enable the edges to be bent downwardly, and forms a closure to prevent the loss of the nails in case the receptacle c_4 , which is usually a paper 50 bag, should break. It will be seen that the peripheral edges of the disk k will be in contact with the inner surface of the roll in which the container is placed, thus forming, with the disk d , the ends of a cylindrical 55 cavity of which the inside of the roll forms the sides.

In use, any one of the types of retainer members illustrated and described above is 60 inserted in the substantially cylindrical cavity or hollow in the roll of roofing or construction material. Such retainer members are so designed and constructed that the end members are smaller than the interior diameter of the cavity in the roll of construction 65 material, while the transverse distance be-

tween the tension members is considerably larger than the interior diameter of the cavity in the roll. Accordingly, when the retainer member is inserted into the cavity of the roll, the lateral tension members are 70 compressed and, therefore, serve to locate or position the retainer member together with the "trimmings" carried thereby at any position within the cavity of the roll that is desired. 75

In Fig. 8 there is illustrated another modification of my invention wherein the lateral tension members a_6 , which are preferably angular in form, although the bowed or equivalent form may be used with advantage, have their ends a_7 passing through apertures c_6 in the rim c_7 on the container b_6 acting as an end member, while the other ends a_8 press against the grooves g in the end member d_2 , which rests on the receptacle c_5 . 80 By this arrangement, when the retainer member just described is inserted into the roll of roofing fabric, pressure is exerted against the inner walls of the cavity of the roll by the members a_6 , with the additional 85 result that the end members a_8 approach each other, exerting increased pressure upon the grooves g , and thereby cause the members b_5 , c_5 and d_2 to be more compactly held together. 90

Throughout this specification the reference characters "b" refer to receptacles which are made of material, such as wood that is rigid and possesses mechanical strength, while the reference characters "c," 100 except in Fig. 2, refer to receptacles which are made of paper or similar material. 95

What I claim is:

1. As an article of manufacture, a retainer member for a roll of construction material 105 comprising in combination a plurality of end members, and lateral tension means associated therewith, one of said end members constituting a hollow container for holding material to be used in applying the roll. 110

2. As an article of manufacture, a retainer member for a roll of construction material comprising in combination a plurality of end members of smaller diameter than the inner cavity of the roll, and lateral tension means 115 associated with said end members and of a larger transverse dimension than the inner diameter of the cavity of the roll, one of said end members constituting a hollow container for holding material for applying the roll, 120 whereby when the retainer member is inserted into the cavity of the roll the lateral tension means will serve to locate and position said member within the roll.

3. As an article of manufacture, a retainer 125 member for a roll of construction material comprising in combination a plurality of end members, and lateral tension members connected to such end members, one of said end members constituting a container for 130

holding material to be used in applying the roll.

4. As an article of manufacture, a retainer member for a roll of construction material comprising in combination a plurality of end members of smaller diameter than the inner diameter of the cavity of the roll, and lateral tension members associated with said end members, the transverse distance between said tension members being substantially greater than the internal diameter of the cavity of the roll, one of said end members constituting a container for holding material to be used in applying the roll, where-
10 by when the retainer member is inserted into the cavity of the roll the lateral tension members will serve to position and locate said member within the roll.

5. As an article of manufacture, a retainer member for a roll of construction material

comprising, in combination, two end members, and a plurality of outwardly bent, angular, tension members, each of said tension members being fixed at one end in one of said end members, the other end of each ten-
25 sion member being free and the other end member being grooved to receive and position said free ends of the tension members.

6. As an article of manufacture, a retainer member for a roll of construction material comprising in combination a plurality of end members, and lateral tension members connected to such end members, one of said end members constituting a container for holding material to be used in applying the roll, and the other one of said end members
30 being made of wood.

In testimony whereof I affix my signature.

RAY P. PERRY.
